INDUCTION MOTOR.

Application filed May 11, 1917, Serial No. 168,030, and in Germany March 30, 1916.

(GRANTED UNDER THE PROVISIONS OF THE ACT OF MARCH 3, 1921, 41 STAT. L., 1313.)

My invention relates to induction motors and it has particular relation to the secondary windings of such motors.

One object of my invention is to increase the starting torque of induction motors of the type using a permanently closed-circuited winding while retaining good constant-speed characteristics and low starting current.

10 A more particular object of my invention is to obtain a large variation of the resistance of the armature conductors employed in the secondary winding of induction motors, and the like, by increasing the eddy currents induced in the conductors and the resulting current displacement in the conductors.

The foregoing and other objects of my invention will be best understood from the accompanying drawings, wherein

Figure 1 diagrammatically shows a three-phase alternating-current induction motor connected to the line;

Fig. 2 shows a curve diagram of the relation of the torque to the slip of the motor;

Fig. 3 shows resistance curves indicating the necessary variation of the rotor resistance for maintaining predetermined torque conditions;

Fig. 4 shows curves indicating possible variations of the apparent ohmic resistance of the rotor depending upon the slip;

Fig. 5 shows curves indicating the increase of the conductor resistance through current displacement, when ordinary conductors of a rectangular cross-section are used at commercial frequencies;

Fig. 6 shows curves indicating the increase of resistance by current displacement for different subdivisions of conductors in dependence upon the numerical height of the slots;

Fig. 7 shows a transverse section of a slot containing two conductors, the figure serving as a basis for the mathematical explanation of the principles underlying the invention;

Fig. 8 shows a cross-section of a composite conductor, partly of electrically and partly of magnetically good conducting material;

Fig. 9 shows a longitudinal section of a

squirrel-cage rotor having composite conductors, such as are shown in Fig. 8; and

Fig. 10 is a transverse section of a slot on the line X—X in Figure 9.

If it is desirable, for controlling purposes of some sort, to have the motor develop its highest possible torque within the entire range of speeds, it is necessary to vary also the resistance of the entire secondary circuit of the motor, either continuously or at very small intervals, and always in proportion to the respective slip. The heavy-line curve r shown in Fig. 3 of the drawings represents the variations of resistance depending on the speed required for a given motor in such case; the corresponding torque curve is shown in Fig. 2 in a heavy dotted line d .

If it is desired to start the motor with a torque other than the maximum, the resistance may be chosen at a value different than that given by curve r . For instance, in employing a resistance which is varied according to the thin curves r_1 or r_2 (Fig. 3), the torque curves d_1 or d_2 , drawn in thin dotted lines, in Fig. 2 are obtained. In the vicinity of the synchronous speed it is not possible of course to reduce the total resistance of the rotor circuit to zero because of the internal resistance r_0 of the secondary winding which necessarily must be left in the circuit, and which produces the normal slip of the motor.

As is well known, this failure of the asynchronous motor to start with a considerable torque without external resistances in the rotor circuits forms a decided disadvantage, as it renders necessary the use of slip rings and of special exterior switching devices and resistances for the rotor circuit. In a limited number of cases the low starting torque, produced by starting a rotor without external resistance, according to the heavy-lined starting curve of Fig. 2, for instance, will suffice, but even then it becomes necessary in most cases to make the inner rotor resistance greater than is desirable for normal working conditions.

Many attempts have been made to dispense with the exterior starting resistance and the slip rings of the motor, either by disposing the resistances and the switches controlling them within the interior of the

rotor, or by increasing the effective rotor resistance by connecting different parts of the winding in opposition. It has further been proposed to provide the rotor with a plurality of windings, a winding having a low resistance for use under normal working conditions and another winding having a far higher resistance designed to take care of the starting torque.

10 The solutions of the starting problem mentioned in the first instance do not give nearly the advantages, so far as simplicity is concerned, which are gained by the squirrel-cage motor, which latter is adequate for normal 15 work and has the most favorable efficiency. The solutions mentioned in the second instance have shown the effect of materially impairing the normal working conditions of the motor in the small number of cases where 20 these expedients have been actually employed in practice, since it has proven to be impossible to dispose the several windings in equally favorable positions on the periphery of the rotor and, as is well known, 25 the quality of an asynchronous motor depends to a very large degree upon such disposition of the windings.

It has finally been proposed, in order to 30 simplify at least to some extent the starting 35 of asynchronous motors, to vary the exterior starting resistances automatically instead of by hand, for instance by making use of the increase of resistance of metallic conductors on being gradually heated by the current 40 passing through them, or by taking advantage of the skin effect raising resistance of the conductors at higher frequency. However these constructions do not admit the use of the simple squirrel-cage rotor.

45 According to my invention, the problem of controlling asynchronous motors at any desirable torque is solved by artificially increasing the ohmic resistance of the armature conductors, necessary for generating the 50 normal torque, by means of current displacement in the slots, whenever a considerable deviation from the synchronous speed has occurred. By the term "current displacement" I mean the crowding of the current 55 towards the outer portions of the conductor similar to the manner in which the so-called "skin effect" manifests itself. By such current displacement the outer portions of the conductor have a large specific current density and thus the ohmic resistance of the conductor is increased.

60 In a motor in accordance with my invention all slip rings are dispensed with as well as all exterior controlling resistances and 65 contacts. It may be provided in the practically simplest manner with a squirrel-cage rotor having plain end rings. At normal, almost synchronous speed it has an exceedingly low slip, not greater than the slip of a slip ring or squirrel cage rotors used hereto-

fore, and in most cases even a by far smaller slip. Furthermore, it has a very strong torque at all speeds, the torque remaining approximately at its pull-out value over the entire speed range (d, Fig. 2). In the motor 70 according to my invention, therefore, the most economical and safe construction is combined with the simplest mode of control in starting as well as in reversing, even in reversing to different speeds, provided the 75 pole connections in the stator are changed.

In order to facilitate the understanding of my invention I have plotted in Fig. 4 of the drawings a sample of the variations of the ohmic alternating-current resistance of 80 different slot conductors, for a particular size of motor, plotting the resistance-variations as a function of the secondary frequency or slip s . The rate of the variations of the resistance caused by the current displacement in the slot conductors may, depending upon the particular construction of the motor, approach very nearly the desired rate of change shown in Fig. 3, the resistance at small slips remaining substantially constant within a wide range, whereas it increases very largely at great slips. Polyphase motors for modern requirements regarding overload capacity and normal slip, 90 require a rotor resistance at starting which is a rather high multiple of the normal resistance, from five-fold, in very small motors to fifty-fold in very large motors. In medium-size motors a fifteen-fold increase of the resistance usually is desirable. 100

In Fig. 5 of the drawings the figures for the increase in resistance by means of current displacement are given as obtained in a typical prior-art squirrel-cage rotor of medium size, provided with conductors of rectangular section, this increase being already greater than in the case of conductors of circular section. It is further assumed that copper of high conductivity, an insulation of very small thickness and a working frequency of 50 periods per second are used so as to create the highest possible current displacement. The height of the bars is assumed to be 3 centimeters (1.15 in.), this being, to all appearances, the greatest height used up to the present in squirrel-cage rotors. 110

The values of the resistance r plotted in Fig. 5 show that even in this extreme case and under expressly favorable conditions the increase of resistance does not by far reach the value required in the service described above. Instead, for instance, of a fifteen fold resistance increase only a three fold resistance increase is obtained. These figures become still more unfavorable, if, as usual, the resistance of the rotor and rings is made very high, so that the increase of the resistance in the bars has a relatively small effect, forming only a small percentage of the total rotor resistance. For in- 120 125 130

stance, if the resistance of the end rings is twice that of the rotor conductors, the variability in the example here chosen will only reach the value shown in Figure 5 in dotted lines. Accordingly, as everybody skilled in the art knows, normal squirrel-cage rotors do not develop any considerable starting torque. In order to obtain it, I artificially increase the current displacement.

10 The simplest way of attaining this end is the use of conductor bars having a greater sectional height. In the armature described above for instance a sectional height of copper bars of about 5 centimeters (2 in.) 15 would produce a five-fold increase of resistance, by reason of current displacement. In small motors this would be quite sufficient, but in the rotors of such motors it is impossible to arrange slots having the necessary 20 depth to accommodate bars of such height. For motors of larger size, the sectional height of the bars would have to be increased quite enormously, for instance to 15 centimeters (5.75 inches) in order to produce 25 a fifteen-fold increase in resistance. Such abnormal increase in conductor height obviously renders the construction of the rotors difficult.

30 In order to increase the displacement of current I prefer to dispose a plurality of conductor bars in each slot, one below the other. These bars however are not simply placed in parallel but are arranged in such a manner,

for instance by series connection, that the distribution of the currents over the single 35 individual conductors which prevails at lower frequencies, remains unchanged also at high frequencies.

Contrary to a far spread theory the alternating current resistance, in the case where 40 the current displacement is considerable, is not diminished at first by such a subdivision 45 of the conductor bars, but is very materially increased. Only when the conductors are subdivided to a very high degree, a considerable diminution of the alternating current resistance is obtained, such a diminution ordinarily forming the reason for such subdivision. For instance with a total sectional 50 height of 8 centimetres (5 in.) of the copper 55 in the slot, such as can still be obtained in a large type of motors, the use of a single copper bar will result only in an eight fold increase of resistance, whereas if the most favorable number of bars (four) is employed, one on top of the other, nearly the twenty fold resistance at the moment of starting is obtained. Such an increase of 60 resistance however is sufficient for almost any large size motor.

The effect of the current-displacement, or eddy currents, in increasing the resistance of a radially-subdivided rectangular conductor embedded in an armature slot, such as shown in Fig. 7, when traversed by alternating 65 currents, may be expressed by the formula

$$(1) \quad \frac{W}{W_0} = H \frac{\sin h2H + \sin 2H}{\cos h2H - \cos 2H} + \frac{m^2 - 1}{3} 2H \frac{\sin hH - \sin H}{\cos hH + \cos H}$$

70 where W is the resistance of the conductor when traversed by alternating current having a frequency f cycles per second, W_0 is the resistance of the conductor when traversed by direct current, m is the number of radial subdivisions and H is, what may be termed, "numerical conductor height" and is defined by

$$(2) \quad H = 2\pi\sqrt{\frac{f}{AB}}$$

75 where A is the ohmic resistance of a part conductor per unit length, in a longitudinal direction, (taken in absolute units), and B is the magnetic reluctance of the space occupied by a unit length of a part conductor in a direction transverse to the slot. The values of A and B may be expressed by

$$(3) \quad A = \frac{s}{hd}$$

$$(4) \quad B = \frac{b}{h\mu}$$

90 where h is the height of a part conductor in centimeters, d is the thickness of the con-

ductor, b is the width of the slot, s is the specific electrical resistance of the conductor, and μ is the average specific magnetic 95 conductivity of the contents of the slot in a direction transverse to the slot. In the foregoing formulas it has been assumed that the current is uniformly subdivided between the several subconductors.

100 Introducing (3) and (4) in (2) we have

$$(5) \quad H = 2\pi h \sqrt{\frac{d\mu f}{b s}}$$

105

Since the ratio of the conductor thickness (d) to slot width (b) is approximately constant (for thin insulation $\frac{d}{b} = 1$), the "numerical height" of the conductor is proportional to the height of the part conductors and practically independent of the conductor thickness.

110 In order to determine the total height of the conductor, or the depth of the slot, required for a definite resistance increase, and to more clearly bring out the effect of the subdivision of the conductor, we now intro-

duce the total height of the conductor or the depth of the slot

$$(6) \quad t = mh$$

and an analogous value, the "numerical slot height" T

$$(7) \quad T = mH = 2\pi t \sqrt{\frac{d}{b} \cdot \frac{\mu}{s} \cdot f}$$

- 10 The increase in the resistance W may thus be expressed without reference to the frequency, by considering it as a function of an imaginary "total numerical conductor height mH" or "numerical slot depth" T. 70
 15 The actual values of the conductor height h and the slot depth t are then determined from the "numerical" height H or depth T, respectively, and will vary depending on the frequency of the current, and the constants 80 of the material filling the slot.

In Fig. 6 are plotted curves showing the dependence of the resistance ratio $\frac{W}{W_0}$ upon the numerical slot depths T, for different 90 numbers of subdivisions $m=1$ to $m=8$.

For instance, to obtain a fourteen-fold increase in resistance, a numerical slot depth T=14 must be used in case of a single conductor; a numerical slot depth T=9 for a 95 two-part conductor ($m=2$); a numerical slot depth T=6.7 for a three-part conductor, ($m=3$); a numerical slot depth T=6.9 for a four-part conductor, ($m=4$); and so forth. The "numerical slot depth" 6.7 is 100 the minimum value for a fourteen-fold resistance increase.

It thus appears from the curves that, for 105 each desired value of resistance increase from the standstill to the running condition, there exists a predetermined minimum numerical slot depth below which it is impossible to obtain the desired resistance increase through current displacement.

To each minimum value of the numerical or actual slot depth, there corresponds a particular number of subdivisions into which the total conductor height must be divided in order to obtain the desired 110 resistance increase. The minimum numerical slot depth T_{min} is shown, as a function of the resistance increase, by the dotted line which envelopes the curves representing the 115 dependence of the resistance increase upon the number of the subdivisions.

Accordingly, with a motor designed for a definite operating frequency, there exists a definite minimum slot depth, or total conductor height, and a predetermined optimum 120 number of radial subdivisions of the conductor, which will produce the automatic resistance increase of the secondary induction motor winding necessary to give favorable starting and running conditions.

I have found that, independently of the

desired resistance increase, the minimum slot depth is always obtained by making the numerical, or actual, height of the individual part-conductors of the same definite value and using one or more such conductors, one 75 on the top of the other, depending upon the desired resistance increase. The particular value of the height of the part-conductors is obtained by dividing the minimum numerical slot depth T for any particular value of 80 resistance increase, by the corresponding number of subdivisions m. It will be found that we obtain a sectional numerical conductor height H of about 2.1 centimeters, which remains the same for practically any 85 value of resistance increase.

In accordance with my invention, the secondary member of the induction motor is provided with a winding designed to automatically give the desired resistance increase between the starting condition, when the current in the winding has the full line frequency, and the running condition, when the slip-frequency of the current is very low, by making the total conductor height and 90 the number of subdivisions in the conductor such that the numerical slot depth is approximately equal to the minimum corresponding to the required resistance increase 95 by current displacement. The numerical height H of the part-conductors is then approximately 2.1 centimeters. The value of the numerical conductor height 2.1 may be slightly departed from, and quite favorable proportions are obtained in practice when 100 the numerical height of the part-conductor ranges between 2 and 2.5 centimeters.

In order to obtain the above-described 105 automatic adjustment of the resistance necessary to give favorable starting and running conditions in motors operating on commercial frequencies and using copper for the secondary winding, the slot depth must be made considerably greater than in the ordinary motors used heretofore. If such 110 motors are designed in accordance with the recognized principles of economy in the materials, there is obtained a rotor having wide teeth and low tooth saturation and narrow conductors of relatively great total 115 height. The low tooth saturation results in decreased flux-pulsation losses and improves the efficiency of the motor.

The part conductors, which are arranged 120 in the slots of the rotor, one on the top of the other, are suitably connected to constitute closed-circuited windings responsive to the field induced by the primary member, care being taken to secure substantially equal distribution of the current among the several 125 subconductors. If the conductors are connected as a phase winding, part conductors disposed at different heights in the several slots are connected in series so that the total electromotive forces induced in each closed- 130

circuited part circuit are equal. In case of a squirrel-cage winding, the part conductors are transposed within each slot, as indicated in Fig. 9, so that the electromotive forces induced in each part conductor are equal.

In distinction from the use of transposed windings in the prior-art machines for diminishing the current displacement, the transposition is used in the motors constituting the subject matter of my invention for increasing the current displacement.

For commercial frequencies (about 50 cycles) and non-magnetic copper conductors

$$15 \quad (s = 2000 \frac{\text{cm.}^2}{\text{sec.}} \text{ and } \mu = 1),$$

the actual conductor height h and slot depth become approximately equal to the numerical conductor height H and slot depth T , respectively, as will be seen from equation (7), which becomes

$$T = t \sqrt{\frac{4\pi^2 \cdot 50}{2000}}.$$

25 If a considerable resistance increase is desired, the required slot may thus become too deep for practical constructions. According to my invention, a relatively high value of the numerical slot depth is obtained with 30 relatively small actual slot depth by increasing the magnetic conductivity of the slot contents, an increase in the conductivity μ increasing the factor with which the actual slot depth t , in equation (7), must be multiplied to obtain the numerical slot depth.

The simplest way for increasing the magnetic conductivity of the contents of the slot is to make the conductors of iron. The electric conductivity of iron conductors is, 40 however, so small that the motor has too high losses near synchronism and, accordingly, the preferred form of my invention employs conductors which are partly of a material of good electric conductivity and 45 partly of a material of good magnetic conductivity. Such conductor is shown in Fig. 8, wherein layers of magnetic material v are disposed between the part-conductors w of good conducting material, the individual 50 part-conductors being suitably connected into a closed circuit, as explained above. In this way, I am able to obtain, with an actual slot depth of 2 to 3 centimeters, a numerical slot depth of 8 to 12 centimeters, 55 which is sufficient to produce a 12 to 18 fold increase in resistance at commercial frequencies.

Composite conductors may also be used in connection with squirrel-cage rotors, such 60 as shown in Figs. 9 and 10, wherein two part-conductors w of good conducting material are disposed one on the top of the other in the slots and transposed in the middle so that each part-conductor is located 65 for one half of its length in the lower por-

tion of the slot and for the other half of its length in the upper portion, in order to secure equal distribution of the current between the two part-conductors. Each part-conductor is split in the middle and an iron 70 filler v is embedded between the two portions of each part-conductor to increase the magnetic conductivity of the slot in accordance with the explanations given hereinabove. The magnetic fillers v preferably 75 assist in conducting the induced currents, thus utilizing all of the materials filling the slot.

I claim:—

1. In an asynchronous machine, a secondary member comprising a magnetic core having a plurality of peripherally disposed slots, a short-circuited induced winding for said member comprising a plurality of conductor bars arranged one on the top of the other in said slots and so connected into closed circuits that the induced current is substantially equally distributed between all of the bars of a slot and magnetic layers disposed between said bars.

2. An asynchronous motor designed to operate with currents of a predetermined line frequency, comprising a primary member and a secondary member, said secondary member comprising a cylindrical magnetic core having slots disposed near the periphery thereof, a permanently closed-circuited induced winding in said slots, said winding comprising a plurality of conductors radially disposed in the slots one on the top of the other and so arranged that the induced currents are equally distributed between the individual conductors, magnetic material interposed between said individual conductors to increase the magnetic field across the slots, the height of the individual conductors and the number of individual conductors disposed on the top of each other in a slot being such that, for a given material of the slot contents, the current displacement produces a predetermined resistance increase of the secondary winding between the starting condition and the normal running condition with a minimum total slot depth.

3. An asynchronous motor designed to operate with currents of a predetermined line frequency, comprising a primary member and a secondary member, said secondary member comprising a cylindrical magnetic core having slots disposed near the periphery thereof, a permanently closed-circuited induced winding in said slots, said winding comprising a plurality of conductors radially disposed in the slots one on the top of the other and so arranged that the induced currents are equally distributed between the individual conductors, magnetic material interposed between said individual conductors to increase the magnetic field across the slots, the numerical height of the individual con-

ductors with the associated magnetic material being between 2 and 2.5 at line frequency.

4. In an induction motor designed to operate economically on a predetermined line frequency, a secondary member comprising a cylindrical magnetic core having a plurality of slots near the periphery thereof, a squirrel-cage winding comprising relatively high conductors disposed in said slots and short-circuiting rings at the ends of the core, each conductor being radially subdivided into a plurality of part-conductors, said part-conductors being transposed within the slots so that each part-conductor has induced therein approximately the same voltage, magnetic material interposed between said part-conductors to increase the magnetic field across the slots, the numerical height of the individual part-conductors with the associated magnetic material being approximately 2.1, and the total conductor height being sufficient to produce a material resistance increase of said squirrel-cage winding between the normal running and starting conditions.

5. In an induction motor, a magnetic member having a plurality of relatively deep slots, a squirrel-cage winding comprising a pair of relatively deep conductor bars per slot, whereby said winding has relatively high reactance and relatively large eddy current losses when the secondary current is of relatively high frequency, said conductor bars being offset at their center and arranged so that the top bar becomes the bottom bar and the bottom bar becomes the top bar, the conductor bars in the same slot being insulated from each other and connected at their ends to common end rings, and layers of magnetic material embedded in said bars.

6. In an induction motor, a magnetic member having a plurality of relatively deep slots, a squirrel-cage winding having deep conductors positioned in said slots whereby said conductors have a high reactance and a large eddy current loss when the secondary current is of relatively high frequency, each conductor of said squirrel-cage winding being subdivided into a plurality of bars vertically arranged and insulated from each other, means whereby the bars of the same conductor carry substantially the same current, and magnetic material interposed between the individual bars.

7. In a dynamo-electric machine, a magnetic core having slots, a winding comprising a plurality of highly conductive bars disposed adjacent to each other in said slot, means for causing the adjacent bars to carry equal currents, notwithstanding the differences in the amount of flux interlinked with the individual bar, and magnetic material interposed between adjacent conducting bars.

8. In an electric machine, a magnetic core

and a plural-strand winding on said core, the individual strands being transposed throughout the winding to obtain substantially equal flux linkage for each individual strand and magnetic material embedded between the strands.

9. In a short-circuited armature for asynchronous motors having a slotted iron core, at least one conductor bar in each slot composed of a plurality of good conducting elements disposed one above the other to cause displacement of current and increase of the conductor resistance at great slips, the numerical height of said conductor elements being greater than 2 and smaller than 2.5, and magnetically conducting layers embedded between said conductor elements to increase the slot leakage and thereby the current displacing property of said elements.

10. In a short-circuited armature for asynchronous motors having a slotted iron core, at least one conductor bar in each slot composed of a plurality of good conducting elements disposed one above the other to cause displacement of current and increase of the conductor resistance at great slips, and being transposed relatively to each other in the slot at least once throughout the length of the slot, the numerical height of said conductor elements being greater than 2 and smaller than 2.5, and magnetically conducting layers embedded between said conductor elements to increase the slot leakage and thereby the current displacing property of said elements.

11. An induction-motor secondary member comprising a magnetizable core having a plurality of peripherally disposed slots or perforations and a plurality of conductor bars of good electrical conductivity and magnetic bars or bridges of good magnetic conductivity disposed at different radial heights in said slots or perforations, said conductor bars, at least, being so connected into closed circuits that the induced current is substantially the same in all of the bars, the number of superposed bars and the radial height of each bar being so chosen that the depth of said slots or perforations is substantially a minimum for any given ratio of the line-frequency or starting resistance to the slip-frequency or running resistance of said motor secondary member.

12. An induction-motor secondary member comprising a magnetizable core having a plurality of peripherally disposed slots or perforations and a short-circuited induced winding comprising a plurality of conductor bars disposed at different radial heights in said slots or perforations and so connected into closed circuits that the induced current is substantially the same in all of the bars, the number of superposed bars and the radial height of each bar being so chosen that the depth of said slots or

perforations is substantially a minimum for any given ratio of the line-frequency or starting resistance to the slip-frequency or running resistance of said bars, each of said bars comprising two spaced, parallel portions of a material having good electrical conductivity and a filler of magnetic material disposed therebetween.

13. In a squirrel-cage induction motor having a high starting torque and a low slip, a squirrel-cage secondary winding comprising composite bars, each bar comprising two spaced, transposed portions of a material having good electrical conductivity and a filler of magnetic material disposed therebetween, the spaced parallel portions being joined together at the ends.

14. In a squirrel-cage induction motor having a high starting torque and a low slip, a squirrel-cage secondary winding, each bar of said winding comprising a plurality of transposed bars, each of the transposed bars comprising two spaced, parallel portions of a material having good electrical conductivity and a filler of magnetic material disposed therebetween, the spaced parallel portions being joined together at the ends.

15. In a squirrel-cage induction motor

having a high starting torque and a low slip, a squirrel-cage secondary winding comprising composite bars, each bar comprising two spaced, parallel portions of a material having good electrical conductivity and a filler of magnetic material disposed therebetween, the spaced parallel portions being joined together at the ends, and the height, permeability and specific resistance of the composite bars being such that the numerical height, as defined in the specification, is of the order of 2.

16. In a squirrel-cage induction motor having a high starting torque and a low slip, a squirrel-cage secondary winding, each bar of said winding comprising a plurality of transposed bars, each of the transposed bars comprising two spaced, parallel portions of a material having good electrical conductivity and a filler of magnetic material disposed therebetween, the spaced parallel portions being joined together at the ends, and the height, permeability and specific resistance of the composite bars being such that the numerical height, as defined in the specification, is of the order of 2.

REINHOLD RÜDENBERG.
